UNITED STATES PATENT OFFICE

MORRIS LUCOMLIN, OF NEW YORK, N. Y.

DESIGN FOR A COSTUME JEWELRY CLASP

Application filed October 22, 1930. Serial No. 37,344. Term of patent 3½ years.

To all whom it may concern:

Be it known that I, MORRIS LUCOMLIN, a citizen of the United States, and a resident of New York, in the county of Bronx and State of New York, have invented a new, original, and ornamental Design for Costume Jewelry Clasp, as shown, of which the following is a specification, reference being had to the accompanying drawings, forming part hereof.

I claim:

The ornamental design for a costume jewelry clasp as shown.

MORRIS LUCOMLIN.
